UNITED STATES PATENT OFFICE.

ROBINSON P. SEARLE, OF TOLEDO, OHIO.

COMBINED CIGARETTE AND MATCH CASE.

Application filed February 8, 1924. Serial No. 691,336.

To all whom it may concern:

Be it known that I, ROBINSON P. SEARLE, a citizen of the United States, and a resident of Toledo, in the county of Lucas and State 5 of Ohio, have invented a new and useful Combined Cigarette and Match Case, which invention is fully set forth in the following specification.

This invention relates to a combination receptacle or case adapted to hold both cigarettes and matches, and has for its primary object the provision of a novel device of this character which comprises two hingedly connected members, one for carrying cigarettes 15 and one for carrying matches, and adapted to be held, and released for opening, by one hand, the two members when released being adapted to automatically assume positions whereby both the cigarettes and matches are 20 held in easily accessible upright positions, thus rendering the device particularly valuable for use by motorists and others where one hand is engaged in driving or in some other occupation.

25 A further object of the invention is the provision of a device of the class described adapted to receive and hold cigarettes and matches in their original packages or boxes. Further objects and advantages of the invention will be apparent from the following 30 description thereof.

While the invention in its broader aspect is capable of embodiment in numerous forms, a preferred embodiment thereof is 35 illustrated in the accompanying drawings, in which,—

Figure 1 is a side elevation of a case embodying the invention and in closed position. Fig. 2 is an upper end view thereof, Fig. 3 40 is a lower end view thereof with the ash dumping slide in open position, and Fig. 4 is a side elevation of the case.

Referring to the drawings, 1 designates what may be termed the case body and 2 the 45 cover, which are hinged together at 3 and combined to form a closed rectangular case of suitable size and shape to receive an original package 4 of cigarettes 5 in the body member, and a small box 6 of matches 7 in its cover member. The cigarettes are disposed in upright position in the member 1 and the matches are disposed crosswise of the cover member in transverse relation to the cigarettes.

50 The inner faces of the body and cover

members 1 and 2 are disposed on a transverse incline, as indicated at 8 in Fig. 1, with the hinge 3 disposed at the lower end of the incline or considerably closer to the bottom of the case than the upper end of the incline. 60 The lower end of the inclined end of the body member is lower, and the upper end of such end is higher than the height of a package of cigarettes when disposed in the case so that a corner portion of the package projects beyond the inclined end of the body member and so that when such corner portion of the package is torn away, as indicated at 9 in Fig. 4, a portion of the cigarettes are exposed and project at their ends 65 a distance above the inclined end of the body member to facilitate engaging and withdrawing a cigarette from the package. In like manner the long side of the cover member 2 is of greater width than a box of 70 matches, and the short side of such member is of less length than the width of the matches so that a corner portion of the match box projects beyond the inclined edge 75 of the cover member in position to render 80 the matches 7 easily accessible when the projecting corner portion of the match box is broken away, as indicated at 10.

The case members are held closed by a spring catch finger 11, which is fixed at one 85 end to an edge of the case in opposition to the hinge 3 and adjacent to the upper end of the incline 8, and the free end of the catch finger releasably engages over the upper end of the cover member 2. The free end edge 90 of the catch finger is turned up to facilitate engaging the same by the finger of a hand grasping the cover member 2 so that the catch finger may be forced out of engagement with the cover and the member 1 95 opened by gravity without touching the case with the other hand.

A space is provided between the short side edge of the body member 1 and a package 4 of cigarettes disposed therein, and this space 100 is utilized to form an ash receiving receptacle 12 by the provision of a partition 13 in the body member. The upper end of the ash receiving space 12 is open when the cover member is opened, and is closed when said member is closed by reason of a lip 14 at the hinged edge of the cover member standing over the receptacle 12 when the cover member is closed. A lip 15 on the inner side 105 of the long edge portion of the cover member 110

engages the lower edge of a match box 6 to releasably retain the box in the cover. The frictional engagement of the side of the cover member with the match box is also utilized to hold the box in the cover member.

For the purpose of discharging ashes from the receptacle 12, the body member 1 is provided on its bottom with a slot 16, which, when closed, forms the bottom of the receptacle, and when moved outward provides a bottom opening through which the ashes are discharged. The upper end of the cover member 2 may be provided with a slot or opening 17, which exposes a striking surface 18 on the adjacent edge of the match box 6.

It is evident that I have provided a combined cigarette and match case which is adapted to hold both the cigarettes and matches in their original packages and when opened exposes the projecting ends of a plurality of cigarettes 5 and matches 7, both being in upright and easily accessible position to facilitate their removal from the case, and that by grasping the cover portion of the case with one hand the catch 11 may be released by a finger of such hand and the cover is then turned by a movement of the hand so that it stands in substantially right-angular relation to the body member to dispose both the cigarettes and matches in accessible upright position, or the cover member may be held in such a position when the catch finger is released that the body member 1 will swing downward by gravity to open position.

I wish it understood that my invention is not limited to any specific construction, arrangement or form of the parts as it is capable of numerous modifications and changes without departing from the spirit of the claims.

Having thus described my invention what I claim as new and desire to secure by Letters Patent is:

1. A combined cigarette and match case having body and cover members hinged together and meeting along an inclined line, one member being adapted to hold a plurality of cigarettes and the other to hold a plurality of matches with the inclined meeting line of the members intersecting some, at least, of the cigarettes and matches.

2. A combined cigarette and match case having hinged body and cover members meeting along a transverse inclined line, the body member being adapted to receive cigarettes in upright position, and the cover member to receive matches in transverse position over the cigarettes, and said inclined line intersecting portions of the cigarettes and matches held by the case.

3. A combined cigarette and match case having a body member adapted to receive a package of cigarettes in upright position

and a cover member adapted to receive a box of matches in transverse position over the cigarettes, the body and cover members meeting on a transverse incline which intersects respective corner portions of a package of cigarettes and a box of matches carried by the case, the body and cover members being hinged together at the lower end of the incline.

4. A combined cigarette and match case having a body member adapted to receive a package of cigarettes in upright position and a cover member adapted to receive a box of matches in transverse position over the cigarettes, the body and cover members meeting on a transverse incline which intersects respective corner portions of a package of cigarettes and a box of matches carried by the case, the body and cover members being hinged together at the lower end of the incline, and a catch means releasably holding the members in closed relation.

5. A combined cigarette and match case having a body member and a cover member hinged together with their inner ends meeting along an inclined transverse line which line terminates at each end intermediate the length of the case, the body member adapted to hold a package of cigarettes with a corner portion projecting beyond the inclined end thereof and the cover member adapted to hold a box of matches with the corner portion projecting beyond the inclined end of such member, and means for releasably retaining the members in closed relation.

6. A combination cigarette and match case having a body member with an inclined inner end and forming a receptacle for a package of cigarettes and a receptacle in the short edge portion thereof for receiving ashes, a cover member having its inner end inclined to correspond with the inclined end of the body member and hinged at the lower end of its incline to the lower end of the body member incline, said cover member being adapted to hold a box of matches in transverse relation to the cigarettes, means for releasably retaining the members in closed relation, and means attached to the cover member and operable to close the upper end of the ash receptacle when the cover member is in closed position.

7. A combination cigarette and match case having a body member with an inclined inner end and forming a receptacle for a package of cigarettes and a receptacle in the short edge portion thereof for receiving ashes, a cover member having its inner end inclined to correspond with the inclined end of the body member and hinged at the lower end of its incline to the lower end of the body member incline,

said cover member being adapted to hold a box of matches in transverse relation to the cigarettes, means for releasably retaining the members in closed relation, and means attached to the cover member and operable to close the upper end of the ash receptacle when the cover member is in closed posi-

tion, and means closing the lower end of the ash receptacle and operable to open the same.

In testimony whereof, I have hereunto signed my name to this specification.

ROBINSON P. SEARLE.
